INVENTOR
Edward J. Brooks,

Edward J. Brooks.

UNITED STATES PATENT OFFICE.

EDWARD J. BROOKS, OF EAST ORANGE, NEW JERSEY, ASSIGNOR TO E. J. BROOKS & CO., OF NEW YORK, N. Y.

METALLIC SEAL.

SPECIFICATION forming part of Letters Patent No. 295,346, dated March 18, 1884.

Application filed January 16, 1884. (No model.)

To all whom it may concern:

Be it known that I, EDWARD J. BROOKS, a citizen of the United States, residing at East Orange, in the State of New Jersey, have invented a new and useful Improvement in Metallic Seals, of which the following is a specification.

This invention relates to improvements in those "metallic seals" composed, partly, of soft metal—lead being commonly used—and partly of tin or other sheet metal. Various forms of these seals are shown in United States patents already granted for my inventions—viz., No. 178,722, dated June 13, 1876; No. 209,008, dated October 15, 1878; No. 246,068, dated August 23, 1881; No. 254,601, dated March 7, 1882; No. 258,278, dated May 23, 1882; No. 260,279, dated June 27, 1882, and No. 286,775, dated October 16, 1883.

My present invention is more particularly in continuation of my series of inventions relating to what I term "cast-in" seals. A seal of this description is shown in said Patent No. 178,722 at Fig. 21; and the advantages of the peculiarity are set forth in said Patents No. 246,068, No. 260,279, and No. 286,775, which relate exclusively to "lead-and-tin" seals of this cast-in class.

The present invention consists in certain novel combinations, of peculiarly-constructed parts, in a metallic seal of soft metal and sheet metal combined, as hereinafter described and claimed. Its objects are, first, to render the seal secure against stripping, and to manifest the construction by which this is accomplished; secondly, to provide for readily and cheaply making the sheet-metal part of the same of common tin.

A sheet of drawings accompanies this specification as part thereof.

Figure 1 of these drawings is an edge view of a seal illustrating this invention, the same being shown "straight" or flat, as it leaves the factory and is carried by the sealer. Fig. 2 is a longitudinal section of the same "threaded," as for pressing. Fig. 3 is a cross-section on the line 3-3, Fig. 2. Fig. 4 is a face view of the same as applied to a pair of staples and "pressed." Figs. 4^x and 4^y represent magnified sections of the pressed seal, taken, respect-

ively, on the lines *x x* and *y y*, Fig. 4. Figs. 5 and 5^x represent, respectively, an edge view and a face view of the main end of another seal straight, illustrating a modification of the same invention. Fig. 6 represents a longitudinal section of the same threaded; and Fig. 7 is a face view thereof pressed.

Like letters of reference indicate corresponding parts in the several figures.

The two seals shown in the drawings are, in fact, two forms of one and the same seal. In either form this improved seal is composed of a soft-metal part, preferably of lead, indicated by *L*, and a sheet-metal part, preferably of tin, (tin-plate,) indicated by *T*. The lead *L* is cast fast within a holder, *a*, formed in the strip *T*, near one extremity of the latter, and its protruding portion is provided with a threading-hole, *b*, extending therethrough lengthwise of the strip, immediately in front of the plane of the strip end *c*, in which the lead is held. The opposite end of the strip, (marked *d*), termed its "threading end," is of contracted width, and is provided with an anchoring projection, *e*, on its outer side or face, and thus armed is admitted freely by said threading-hole at the threading operation, so as to locate said projection within the lead, as shown in Figs. 2, 3, and 6. The lead is further provided with a central "detective-aperture," *f*, in its top or face, which, after the seal is pressed, as shown in Figs. 4, 4^x, 4^y, and 7, exposes said anchoring projection, so as to manifest the construction of the seal and aid to prevent counterfeiting; and, finally, the threading end of the strip is provided with gage-shoulders *g*, which, coming in contact with the lead in the act of threading the seal, facilitate locating said anchoring projection *e* exactly behind or in line with said detective-aperture *f*, as shown. In either form the strip *T* is first formed complete by known methods, and the seal *L* is cast fast therein, with the aid of a suitable mold. The article is then ready for shipment and use. It is packed and carried straight, as aforesaid, and after passing it through a pair of staples, *s s*, Fig. 4, or applying it in any approved way to any car-door fastening or anything else that can be secured by such a seal, it is threaded, as illustrated by

Figs. 2, 3, and 6, and is then pressed, as illustrated by Figs. 4, 4^x, 4^y, and 7, by means of a suitable seal-press. It may be simply flattened to fasten the seal, said anchoring projection *e* being securely embedded in the lead, so as to preclude stripping, as shown in Fig. 4^x; but for greater security against counterfeiting the pressed lead is preferably provided with distinguishing press-marks *m*, which may 10 be readily indented deeply in the soft leaden face of the seal, as indicated in Fig. 4^x; and the strip is for the same purpose preferably provided, in course of manufacture, with marks *n*, printed, stenciled, or stamped on the 15 tin with suitable water-proof ink, or burned in or shellacked to render them permanent, or with permanent marks *o*, Fig. 6, embossed or otherwise formed in the strip or in the back of the holder *a* in any approved way.

20 In the preferred form (represented by Figs. 1 to 4^x, inclusive) the holder *a* and anchoring projection *e* are both formed by simple bending operations, adapting this form of the seal to be readily and cheaply made of common 25 tin; and the escape of the lead laterally is guarded against by punching a hole, *h*, in that part of the strip which subsequently forms the holder *a*, this hole and the inwardly-projecting metal therefrom being filled and embraced 30 by the lead, as shown, at the casting operation.

Holes of different shapes may be formed in seals for different users to distinguish them, and this applies also to the detective-aper- 35 tures *e*.

In the modification illustrated by Figs. 5 to 7, inclusive, the holder *a* is of "button" form, or may be compared to the flange end of a hollow-headed metallic cartridge-shell, and 40 may be readily die-formed, like the latter. The anchoring projection *e* of this seal is correspondingly "struck up" in contrast with the bent-up projection of said preferred form.

Soft tin or annealed sheet-iron, or thin brass or copper, may preferably be used in making 45 seals with such button-holders.

The press-marks *m* (shown in Fig. 7) are "4 P. M. 12,12,83, N. Y.," indicating sealed at New York December 12, 1883, at 4 o'clock, afternoon. Such stamped dating-marks are 50 claimed by me in another specification, and form no part of my present invention. They may be stamped on the strip, if preferred, at the sealing operation.

The permanent marks *o* (represented in dotted lines in Fig. 7) are "U. S. C.," for United States Customs.

Having thus described my said improvement in metallic seals, I claim as my invention—

1. The combination, in a metallic seal, of a 60 sheet-metal strip having at or near one end a lead-holder integral therewith, and at its other extremity a threading end provided with an anchoring projection on its face, and a leaden part, cast fast within said holder, and constructed with a threading-hole and a detective-aperture in its protruding face portion, substantially as herein specified, for the purposes set forth.

2. An improved metallic seal composed, as 70 herein specified, of a sheet-metal strip having at or near one end a lead-holder, and at its other extremity a threading end provided with an anchoring projection on its face, and a leaden part, cast fast within said holder, and 75 constructed with a threading-hole and a detective-aperture to receive said threading end and expose its anchoring projection after the seal is pressed, said holder and projection being formed by simple transverse bends, as 80 shown, for the purpose set forth.

EDWARD J. BROOKS.
